Primary Examiner — Cynthia Underwood(74) *Attorney, Agent, or Firm* — McAndrews, Held & Malloy, Ltd.(57) **CLAIM**

The ornamental design for the hose guide, as shown and described.

DESCRIPTION

FIG. 1 is a perspective view of an hose guide.

FIG. 2 is another perspective view of the hose guide of FIG. 1.

FIG. 3 is a top plan view of the hose guide cap of FIG. 1.

FIG. 4 is a rear elevational view of the hose guide of FIG. 1.

FIG. 5 is a left-side elevational view of the hose guide of FIG. 1.

FIG. 6 is a front elevational view of the hose guide of FIG. 1.

FIG. 7 is a right-side elevational view of the hose guide of FIG. 1; and,

FIG. 8 is a bottom plan view of the hose guide of FIG. 1.

The broken lines represent portions of the structure that form no part of the claim; the wavy lines indicate indeterminate length.

The wavy lines represent an unspecified length of the structure, the length of which forms no part of the claim.
